[57] CLAIM

The ornamental design for an arc welding electrode holder, as shown and described.

DESCRIPTION

FIG. 1 is a side elevational view of the arc welding electrode holder, the opposite side being substantially similar thereto.

FIG. 2 being substantially similar to FIG. 1 but with a portion cut away.

FIG. 3 is a top plan view thereof.

FIG. 4 is a bottom plan view thereof.

FIG. 5 is a rear elevational view thereof.

FIG. 6 is a cut away portion of a top plan view thereof taken as on the line VI—VI of FIG. 1 and with the spring removed.

FIG. 7 is a front elevational view thereof.

FIG. 1

FIG. 2
